The ornamental design for an electrical connector comprising a plurality of modular terminal blocks, as shown and described.

DESCRIPTION

FIG. 1 is a bottom plan view of an electrical connector comprising a plurality of modular terminal blocks in accordance with a first embodiment of our new design;

FIG. 2 is a front elevation view thereof;

FIG. 3 is a rear elevation view thereof;

FIG. 4 is a top plan view thereof;

FIG. 5 is a top, right, front perspective view thereof;

FIG. 6 is a bottom plan view of an electrical connector comprising a plurality of modular terminal blocks in accordance with a second embodiment of our new design;

FIG. 7 is a front elevation view thereof;

FIG. 8 is a rear elevation view thereof;

FIG. 9 is a top plan view thereof;

FIG. 10 is a top, right, front perspective view thereof;

FIG. 11 is a bottom plan view of an electrical connector comprising a plurality of modular terminal blocks in accordance with a third embodiment of our new design;

FIG. 12 is a front elevation view thereof;

FIG. 13 is a rear elevation view thereof;

FIG. 14 is a top plan view thereof;

FIG. 15 is a top, right, front perspective view thereof;

FIG. 16 is a bottom plan view of the electrical connector comprising a plurality of modular terminal blocks in accordance with a fourth embodiment of our new design;

FIG. 17 is a front elevation view thereof;

FIG. 18 is a rear elevation view thereof; FIG. 19 is a top plan view thereof;

FIG. 20 is a top, right, front perspective view thereof;

FIG. 21 is a left side elevation view of an electrical connector comprising a plurality of modular terminal blocks in accordance with all embodiments of our new design; and,

FIG. 22 is a right side elevation view thereof.

The broken line portion of the figure drawings is included to show unclaimed subject matter only and forms no part of the claimed design.
